UNITED STATES PATENT OFFICE.

HAZEL C. KENDALL, OF ALLSTON, MASSACHUSETTS, ASSIGNOR TO ALFRED HALL, OF BOSTON, MASSACHUSETTS.

MEANS FOR SUPPLYING MOISTURE.

1,311,652.

Specification of Letters Patent. Patented July 29, 1919.

Application filed October 24, 1916. Serial No. 127,483.

To all whom it may concern:

Be it known that I, HAZEL C. KENDALL, a citizen of the United States, residing at Allston, in the county of Suffolk and State 5 of Massachusetts, have invented certain new and useful Improvements in Means for Supplying Moisture, of which the following is a specification.

This invention has reference to improvements in means for supplying moisture, and while the embodiment thereof disclosed herein is shown in connection with an envelop sealer, its principles are applicable to other devices requiring a supply of moisture.

The main objects of the invention are to provide means of this character which, although extremely simple in construction and efficient in operation, will keep constant the supply of moisture in the moistening pad 20 or other moisture receiving element irrespective of the amount of moisture withdrawn therefrom either by use or evaporation; and which is not affected by movement of the device in which it is embodied so that there 25 is no danger of the fluid being splashed out of its source of supply over the moisture receiving element by a sudden movement thereof.

Other objects of the invention will appear 30 from the following description.

The invention consists primarily in the construction and relative arrangement of two conduits with respect to the moisture receiving element and the source from which 35 the moisture is drawn to said moisture receiving element.

The invention further consists in such other novel features as shall hereinafter be described and pointed out in the claims.

Referring to the drawings:

Figure 1, represents a side elevation of an envelop sealer embodying my invention.

Fig. 2, represents a plan view of same.

Figs. 3, 4 and 5 represent sectional views 45 respectively taken on the lines 3-3, 4-4, and 5-5 of Fig. 2.

Like characters of reference designate corresponding parts throughout.

The envelop sealer shown in the drawings 50 is similar to the one described in my co-pending application, Serial No. 91,236 and is provided with the cylindrical tank 10 which serves as a handle as well as a container for the water or other moistening fluid. Said 55 tank consists of the tube 11 having its rear end closed and its other end counter-sunk

into the plate 12 having the threaded opening 13 closed by the removable air-tight cap 14. Said plate 12 is provided with the forwardly projecting bracket 15 to which the 60 presser-foot 17 is attached.

Secured at one end to the plate 12 is the rectangular moistening pad support 19 of sheet metal on which is sustained the pad 20 by the pocket 21 at its forward end and 65 by the pair of lugs 22 and 23, at its rear end.

The tank 10 is in communication with the moistening pad 20 through the comparatively small conduits 25 and 26, both of which are made in the plate 12, and extend 70 from the lower part of the forward end of said tank to said moistening pad. The conduit or air vent 25 is preferably slightly longer than the conduit 26 and its outer end is located nearer the top of the pad. (Fig. 4.) 75

On the under-side of the tank 10 is secured the post 27.

To fill the tank with water or other fluid, its cap 14 is removed and the fluid admitted through the opening closed thereby, while 80 the tank is held in a substantially upright position. Upon replacing the cap and returning the sealer to its operative position, as shown in Fig. 1, the fluid will flow from the tank through the conduit 26 until the 85 previously moistened pad has become thoroughly moistened thereby and thereafter the flow of fluid through the conduit 26 will be directly proportional to the amount of fluid which is removed from the pad either by 90 use or by evaporation, so that the amount of moisture in the pad remains constant.

The water will naturally flow through the conduit 26 rather than through the conduit 25 as it is the shorter and therefore 95 offers the lesser resistance, and yet both of said conduits are preferably of such a comparatively small diameter that air and water cannot readily flow in opposite directions at the same time through either of them. The weight of the fluid together 100 with the elastic pressure of the comparatively small amount of air above the surface of the fluid in the tank is only sufficient to force the fluid to the outer end of the conduit 26, where a globule thereof starts to form and would form if it was not for the partially moistened pad 20 which absorbs the fluid as it reaches the outer end of said conduit, and as the fluid is thus absorbed, 105 the space in the tank above the fluid is increased, thereby creating a sufficient vacuum 110

therein to allow atmospheric pressure to force air up through the conduit 25 into said space where it will exert an elastic pressure to cause the fluid to flow down into 5 the end of the conduit 26 to take the place of the fluid absorbed therefrom by the pad, and this action will continue to occur while there is fluid in the tank until the pad can absorb no more of the fluid, at which time 10 the flow thereof will cease but will immediately act again upon the removal of water from the pad.

The fact that the flow of the fluid immediately ceases when the pad is thoroughly 15 moistened shows that the capillarity of the pad actuates and regulates the flow of fluid from the outer end of the conduit 26, although the flow of the fluid from the tank to the outer end of said conduit 26 is pre- 20 sumably dependent upon the combined weight of the fluid and elastic pressure of the air in the space above the surface of the fluid.

The post 27 sustains the tank in an in- 25 clined position, when the sealer is placed on a table or other support, to cause the fluid to flow down against the forward end of the tank, thereby submerging the inner ends of the conduits 25 and 26, so that the 30 pad may be continually kept moistened.

It is obvious that the resistance of the two conduits may be varied in other ways than by varying the length thereof.

An important feature of the device is the 35 fact that the two conduits may be and preferably are made of so small a diameter that there is little danger of fluid being splashed out over the moistening pad by a sudden jar thereof.

40 The theory has been suggested that the flow of fluid from the conduit 26 creates a current from the inner end of the conduit 25 to the conduit 26 which results in an action similar to that of an injector which assists in drawing air through the conduit 25.

It has been found in practice that sometimes the flow occurs through the conduit 25 instead of the conduit 26 and, accordingly, I find it is advantageous to locate the outer 50 ends of both conduits against the inner end of the pad with the end of the conduit 25 nearer the top thereof. Also, it is thought possible that when the outer ends of both conduits are thus located that the thorough moistening of the pad tends to seal the air inlet conduit.

While I have shown and described and attempted to explain the theory of operation of but one form of my invention, it is to be 60 understood that I do not limit the invention to this specific form except so far as I specify in the appended claims.

I claim:

65 1. A moistening device of the character described comprising a fluid container and

a moistening pad located below said container, said container having two conduits leading from the interior thereof to said moistening pad, said conduits so arranged and constructed as to maintain said moistening pad in a constant state of saturation by moisture supplied through one of said conduits. 70

2. A moistening device of the character described comprising a fluid container and a moistening pad, said container having two downwardly inclined conduits of comparatively small bore leading from the interior thereof to said moistening pad, said conduits so arranged as to maintain said moistening pad in a constant state of saturation by moisture supplied through one of said conduits. 75

3. A moistening device of the character described comprising a fluid container and a moistening pad, said container provided with two downwardly inclined conduits leading from the interior thereof to said moistening pad below the top surface of said moistening pad, said conduits so constructed 80 and relatively positioned as to maintain said moistening pad in a constant state of saturation by moisture supplied through one of said conduits. 85

4. A moistening device of the character described comprising a fluid container and a moistening pad located below said container, said container having two conduits in juxtaposition leading from the interior thereof to said moistening pad, said conduits so constructed as to maintain said moistening pad in a constant state of saturation by moisture supplied through one of said conduits. 90

5. A moistening device of the character described comprising a fluid container and a moistening pad located below said container, said container having two conduits of different lengths leading from the interior thereof to said moistening pad, said conduits so arranged as to maintain said moistening pad in a constant state of saturation by moisture supplied through one of said conduits. 105

6. A moistening device of the character described comprising a fluid container and a moistening pad located below said container, said container provided with two conduits leading from the interior thereof to a side of said moistening pad, with the outer end of one of said conduits closer to the top surface of said moistening pad than the outer end of the other of said conduits. 110

7. A moistening device of the character described comprising a fluid container and a moistening pad located below said container, said container having two conduits of comparatively small diameter leading from the interior thereof to said moistening pad, with the outer end of one of said con- 120

130

duits closer to the top surface of said moistening pad than the outer end of the other of said conduits.

8. A moistening device of the character described comprising a fluid container and a moistening pad located below said container, said container having two conduits in juxtaposition leading from the interior

thereof to said moistening pad, with the outer end of one of said conduits closer to the top surface of said moistening pad than the outer end of the other of said conduits.

In testimony whereof I have affixed my signature.

HAZEL C. KENDALL.
